Primary Examiner—Stacia Cadmus*Assistant Examiner*—Mimosa De(74) *Attorney, Agent, or Firm*—Pearne & Gordon LLP**CLAIM**

The ornamental design for a wooden glider, as shown and described.

DESCRIPTION

FIG. 1 is a perspective view of a wooden glider according to the present invention;

FIG. 2 is a front elevational view of the wooden glider of FIG. 1;

FIG. 3 is a right side elevational view of the wooden glider of FIG. 1, the left side being a mirror image thereof;

FIG. 4 is a rear elevational view of the wooden glider of FIG. 1; and,

FIG. 5 is bottom view of the wooden glider of FIG. 1. The broken lines shown in the drawing are for illustrative purposes only and form no part of the claimed design.
